CONVERTIBLE CHAIR AND PRIE-DIEU

Charles G. Scheuer, 6548 Christiana Ave.,
Lincolnwood, Ill.

Filed Feb. 23, 1961, Ser. No. 64,033

Term of patent 14 years

(Cl. D15—8)

FIG. 1 is a front elevational view of the convertible chair and prie-dieu comprising my design, the view showing the chair seat in lowered position.

FIG. 2 is a side elevational view of the chair shown in FIG. 1.

FIG. 3 is a rear elevational view of the chair shown in FIG. 1.

FIG. 4 is a top plan view of the chair shown in FIG. 1.

FIG. 5 is a front elevational view of the convertible chair and prie-dieu, the view showing the chair seat in raised position.

FIG. 6 is a side elevational view of the chair and prie-dieu shown in FIG. 5.

FIG. 7 is a top plan view of the chair and prie-dieu shown in FIG. 5.

I claim:

The ornamental design for a convertible chair and prie-dieu, substantially as shown.
